KITE

Edward N. Winslow, Chagrin Falls, Ohio

Application May 16, 1947, Serial No. 748,379

6 Claims. (Cl. 244—153)

1

My invention relates to improvements in kites and is more particularly concerned with kites designed to operate without an auxiliary tail balancing element.

The primary purposes of my invention are to provide a kite of extremely simple construction having no attachment between the frame members and possessed of improved flight characteristics. A secondary purpose is to provide a kite having a pyramidoidal planing surface and wherein the rigid longitudinal frame member serves also as a vertical stabilizing element projecting forwardly of the planing surface.

In the achievement of the purposes I have employed in my kite a transverse strut element adapted to extend the planing surface to the lee of the longitudinal member and being freely movable rearwardly relative to the longitudinal member. This transverse strut element in flight will be subject to stress in compression on the ends rather than subject to a bending force on the ends against the center, as is the case in conventional kites of bent stick construction. The design of the invention embodying these features is such that the component elements may be very light, easily folded for packaging, quickly assembled for flight operations, and both efficient and durable as an airfoil.

To the accomplishment of the foregoing and related purposes, this invention, then, consists of the means hereinafter fully described and particularly pointed out in the claims; the annexed drawings and the following description setting forth in detail certain structures embodying the invention, said disclosed means constituting however, but one of various forms in which the principles of the invention may be used.

In the drawings:

Fig. 1 is a rear view in perspective of the assembled kite;

Fig. 2 is a plan view;

Fig. 3 is a side view taken on the line 3—3 of Fig. 2 and showing one form of flying harness; and

Fig. 4 is a plan view of the covering sheet before application to the frame members.

In Fig. 1 there is shown the structural outline of a preferred form of my invention. A flexible polygonal sheet 10 of paper or other suitable material forms the planing surface. The edges of the sheet 10 are folded over as at 11 to provide a channel for a tensioned light string or filamentary element 12 which extends about the entire periphery of the sheet. The string 12 is contained within the secured fold of the sheet

2

but is not necessarily attached thereto, at least not in such a way that it cannot move slidably in the channel. Although normally a string will be used extending about the edges of a light paper sheet for tensioning effect and strength, if a sheet of sufficient strength is employed, the string may be omitted.

The member 13 is a rigid longitudinal frame support for the sheet 12. This member 13 may vary in dimensions, depending upon the kite size desired and other factors, but for purposes of illustration may be in the nature of two inches in width and one-sixteenth of an inch in thickness when the overall length is about eighteen inches and the sheet width approximately equal to the length or somewhat less. The ends of the member 13 are notched as at 14a and 20a to engage the string 12 at the longitudinal extremities of the sheet. It will be noted that the notches 14a, 20a are located in the after or leeward portion of the end area of frame 13.

Over and upon a triangular area of the frame member 13, extending upwardly from the base 14 to a vertex at 15, a portion of the sheet 10, as indicated by the dotted lines 16 in Fig. 4, is secured with glue or other suitable means to form a triangular keel 17. This member 17 acts as a vertical stabilizer for the kite in flight. The frame member 13 is also tapered in depth rearwardly from the vertex 15 to the after area of the upper end 20. The frame member 13 thus provides a contacting longitudinal support for the sheet 10 throughout the length of its leading or windward edge whereon the sheet is secured.

Since the member 13 should be light in weight and yet sufficiently strong to have the rigidity needed effectively to serve as a frame support, I have folded a portion of the sheet 10 over a triangular area of the frame 13 for two purposes. One purpose is to form the keel 17 as mentioned above. The second purpose is to give additional rigidity to the thin frame member 13. When the sheet is folded over the frame and glued tightly thereto, certain stiffening is added to the thin frame member. Further increased rigidity is imparted when the lateral extensions of the sheet forming the planing surface are stretched tight when the transverse strut structure described below is fitted into position. Because of this truss-like design, the thin frame member is able to resist normal bending movements.

To support the sides of the sheet 10 laterally of the longitudinal frame member 13, there is provided a transversely extending strut structure 21,

the outer ends of which are notched and adapted to engage the tensioned string 12 at the lateral extremities of the sheet. To give additional durability and strength to the kite, the exterior ends of the strut 21 may be fitted in pockets of the sheet adjacent the lateral extremities and may have the filamentary element wrapped about the ends of the strut and tied thereto. This strut structure may be a single element if desired, but, as shown, in the drawings, consists of two partially overlapping sticks 23 and 24.

On opposite sides of each stick there is provided a stop member 26. In assembly the interior end of each stick is disposed against the respective stop member of the other stick and the sticks are overlapped through a portion of their length.

To hold the sticks in overlapped position any suitable interlocking means may be employed, such as a sleeve, but for convenience I have shown, rubber bands 27 of small diameter which can be slipped over the overlapped sticks as at 28 and 29 to hold the sticks in position as a rigid transverse strut structure. Another expedient interlock arrangement is to place the sticks end to end in abutting relationship without overlap and to hold them in this position with a sleeve.

It will be noted that the transverse strut structure 21 is disposed to the lee of the longitudinal member 13 and is attached neither to the member 13 nor to the sheet 10 at any point other than at the lateral extremities of the sheet where the string 12 is engaged. Thus, during flight, the strut structure 21 is freely movable rearwardly relative to the longitudinal member.

When the kite is assembled, the filamentary element or string 12 will be attached at the lateral and longitudinal extremities of the sheet to the strut and frame member ends. The length of the strut structure 21 will be such that a slight tension will be placed upon the string 12 when the strut is set in position. Because of the rearward location of the notches 14a and 20a, the string 12, as contained within the edge folds 11 will lie in approximately a single plane.

For flight operations a flying harness, as shown in Fig. 3 at 31, or a string attached to but one point, can be attached to the longitudinal member 13. Thus, in flight, wind or air forces upon the planing surface will tend to force the lateral corners of the sheet 10 rearwardly. Such movement will increase the tension on string 12 and tend to tighten the sheet edges.

Since the strut member 21 is not attached to frame 13, any movement of the lateral extremities of the sheet 10 rearwardly due to increased air pressure on the planing surface (or low pressure on the leeward side of the sheet) will subject the strut to stress in compression. In kites of conventional design, cross-members have heretofore been either attached to the longitudinal member at the point of intersection, or located windward of the longitudinal member, or attached to the covering material of the kite.

In all these designs air pressure on the planing surface of the kite tends to exert a bending movement on the cross-member of the ends against the center, which thus loosens the tension on the edges of the covering sheet, which in turn allows further bending, etc.

I have found that the feature of automatic self-adjustment of the tension upon the string 12 by rearward movement of the member 21 keeps the sheet 10 taut and thus permits smooth flow of air to the edges of the kite. Conventional kites

have an almost inevitable tendency to form concave pockets on the windward side of the covering sheet between the peripheral string and the frame members. These pockets reduce to a great extent the efficiency of the airfoil and invite instability in flight characteristics.

This automatic adjustment in flight feature also helps the kite to have such buoyancy that its flying position approaches a vertical angle above the controller, with the appreciable deviation caused by wind drift of the kite, and its controlling string, and the weight of the string.

Referring now to the shape of the windward side of the sheet 10 when the kite is assembled for flight, it will be seen that the planing surface has a pyramidaloid appearance. In the embodiment shown in the drawings and windward surface of the kite will present four separate planes intersecting at the vertex 15 which will normally be located forwardly of the intersection of the longitudinal and transverse members.

Wind forces and thermal currents striking the planing surface of the kite will be split by the keel or vertical stabilizer 17 and diverted to the edges of the kite by the slanting surfaces of the sheet. Thus effective flying balance can be obtained without resort to auxiliary tail elements to reduce lateral diving tendencies usual in kites of conventional design.

While there has been shown and described a four-sided kite, it will be understood that other shapes can be employed within the scope of the invention; such, for example, as a kite corresponding in shape to a conventional airplane viewed in plan.

Other modes of applying the principles of my invention may be employed instead of the one explained, change being made as regards the structure herein disclosed, provided the means stated by any of the following claims or the equivalent of such stated means be employed.

I therefore particularly point out and distinctly claim as my invention:

1. In a kite of the type described, a polygonal flexible sheet, means for supporting the sheet in the form of a planing surface comprising a longitudinal frame member attached at its ends to the opposite most distant longitudinal extremities of the sheet, a transverse member attached at its ends to the lateral extremities of the sheet, said transverse member being disposed to the lee of the longitudinal member and translatable rearwardly relative to the longitudinal member when wind forces in flight urge the lateral extremities of the sheet rearwardly.

2. In a kite of the type described, a flexible sheet of polygonal shape, means for supporting the sheet in the form of a planing surface comprising a continuous filamentary element extending about the periphery of the sheet and secured thereto, a longitudinal frame member attached at its ends to the filamentary element at the opposite most distant longitudinal extremities of the sheet, a transverse member attached at its ends to the filamentary element at the opposite lateral extremities of the sheet, said transverse member being disposed to the lee of the longitudinal member and translatable rearwardly relative to the longitudinal member when wind forces in flight urge the lateral extremities of the sheet rearwardly.

3. In a kite of the type described, a polygonal flexible sheet, means for supporting the sheet in the form of a planing surface comprising a longitudinal frame member attached at its ends to the

Opposite most distant longitudinal extremities of the sheet, a portion of said longitudinal frame member having part of the sheet secured upon it to form a triangular keel converging from the base of said frame member upwardly and projecting forwardly of the planing surface of the sheet, a transverse member attached at its ends to the lateral extremities of the sheet, said transverse member being disposed to the lee of the longitudinal member and freely movable rearwardly relative to the longitudinal member.

4. In a kite of the type described, a flexible sheet of polygonal shape, means for supporting the sheet in the form of a planing surface comprising a continuous filamentary element extending about the periphery of the sheet and secured thereto, a longitudinal frame member attached at its ends to the filamentary element at the opposite most distant longitudinal extremities of the sheet, a portion of said longitudinal frame member having part of the sheet secured upon it to form a triangular keel converging from the base of said frame member upwardly and projecting forwardly of the planing surface of the sheet, a transverse member attached at its ends to the filamentary element at the opposite lateral extremities of the sheet, said transverse member being disposed to the lee of the longitudinal member and freely movable rearwardly relative to the longitudinal member.

5. In a kite of the type described, a flexible polygonal sheet, a filamentary element extending about the edges of the sheet and secured therewith, means for supporting the sheet in the form of a planing surface comprising, a longitudinal frame member attached to the filamentary element at the opposite most distant longitudinal extremities of the sheet, a stiff transverse strut structure adapted to engage the filamentary element at the opposite lateral extremities of the sheet, with said transverse strut structure being disposed to the lee of the longitudinal member and freely movable rearwardly relative to the longitudinal member, said longitudinal frame member being a thin rigid vertical plate forming

- on its leading edge a contacting support for said flexible sheet throughout its length, and giving a pyramidoidal form to the planing surface of said sheet with the vertex of the pyramid located forward of the intersection of the longitudinal member and the transverse strut structure, a portion of said longitudinal frame member having part of the sheet secured upon it to form a triangular keel projecting forwardly of the planing surface of said sheet and extending from the base 10 of said member to said vertex, said frame member being tapered in depth from said vertex to its uppermost longitudinal extremity.
6. In a kite of the type described, a polygonal flexible sheet, a filamentary element extending about the edges of the sheet and secured therewith, means for supporting the sheet in the form of a planing surface comprising a longitudinal frame member attached at its ends to the filamentary element at the opposite most distant 15 longitudinal extremities of the sheet, a lateral strut structure for the sheet comprising two sticks extending transversely to the longitudinal member, one end of each stick being adapted to engage the filamentary element at the opposite lateral 20 extremities of said sheet, stop members on opposite sides of said sticks, and means to hold said sticks in overlapped relationship through a portion of their length with the non-engaged end of each in abutting position against the stop member of the other stick, said lateral strut structure 25 being disposed to the lee of the longitudinal member and freely movable rearwardly relative to the longitudinal member.
